W. H. MASON.

Car Wheel.

No. 87,180.

Patented Feb. 23, 1869.

WILLIAM H. MASON, OF BOSTON, MASSACHUSETTS.

Letters Patent No. 87,180, dated February 23, 1869.

IMPROVED RAILWAY-CAR WHEEL.

The Schedule referred to in these Letters Patent and making part of the same.

To all whom it may concern:

Be it known that I, WILLIAM H. MASON, of Boston, in the county of Suffolk, and Commonwealth of Massachusetts, have invented a new and useful Improvement in Car-Wheels; and I do hereby declare that the following is a full and exact description thereof, reference being had to the accompanying drawings, and the letters of reference marked thereon.

To enable others skilled in the art to make and use my invention, I will proceed to describe its construction.

The object of my invention is to provide a double-spoked car-wheel, which has the spokes directly connected with the hub and felloe, and which is so contrived that it can be cast in one piece, with a single green-sand core, thereby making a very great and important saving in expense of construction, while it has all the requisite strength, with less weight of metal than other wheels.

In the construction of my wheel, I use two sets of spokes, as shown by the drawings. They are connected directly with the hub, on its opposite sides, and pass thence to the felloe of the wheel, the spokes of each set being arranged opposite to each other, so that spaces are left between the spokes, through the wheel, the whole distance from the hub to felloe, or the whole length of the spokes.

This construction enables me to dispense, in moulding, with a dry-sand core, and connect the opposite sides of the mould by a green-sand core, a method less expensive than the other, and which cannot, to my

knowledge, be used in spoked wheels as now constructed.

In the accompanying drawings—

Figure 1 represents a side view of the wheel or plan of the exterior surface on its inner side.

Figure 2 is a transverse section at the line A. B, from the circumference to the centre of the wheel, showing the curves, or corrugations in the outer or inner surfaces of the spokes.

a a a are the curves above mentioned.

b is a hub.

The object of the curves, or corrugations of the spokes (to prevent cracking or warping when the iron is cooling) is too well known, and the device is too common to need a description. Still, their use is necessary in my wheel, on account of the length of its spokes.

I do not claim all cast car-wheels having spokes, nor all cast car-wheels having curved spokes; but

I do claim a cast car-wheel in one piece, having two sets of curved spokes, each set arranged upon the opposite sides of the wheel from the other set, and the spokes of one set directly opposite the spokes of the other, when the spokes extend from the hub to felloe, all substantially as shown, and to accomplish the purpose specified.

WM. H. MASON.
